UNITED STATES PATENT OFFICE.

IVAN A. HARRISBERGER, OF FLORENCE, COLORADO.

SMOKING PIPE.

Application filed March 16, 1926. Serial No. 25,038.

An object of this invention is to provide an improved construction for tobacco or other smoking pipes wherein provision is made for elimination from the smoke duct of saliva and the objectionable oils resulting from combustion.

A further object of this invention is to provide an improved construction for tobacco or other smoking pipes wherein the smoke duct is interrupted intermediate of the pipe bowl and mouth-piece to preclude passage of the deleterious oils of combustion from the bowl to the mouth-piece or of saliva from the mouth-piece to the bowl.

15 A further object of this invention is to provide means in a tobacco or other smoking pipe whereby saliva and the deleterious oils of combustion may be trapped before reaching the combustion chamber and the 20 mouth-piece respectively and conducted to a receptacle apart from the smoke duct.

A further object of this invention is to provide means in a tobacco or other smoking pipe for deodorizing and neutralizing 25 the fouling elements generated within said pipe.

Another object of this invention is to provide an improved construction for a 30 moisture trap adapted to be incorporated in a tobacco or other smoking pipe.

35 My invention consists in the construction, arrangement and combination of elements hereinafter set forth, pointed out in my claims and illustrated by the accompanying drawing, in which—

40 Figure 1 is a vertical section of one form of pipe embodying my invention. Figure 2 is likewise a vertical section of another form of pipe embodying my invention. Figure 3 is a side elevation and Figure 4 an end view, on an enlarged scale, of the moisture trap comprising an essential part of my invention.

45 In the construction of my improvement as shown, the numeral 10 indicates the bowl or body portion of a pipe, said body portion being of any suitable material and of any desired shape and contour and being provided with a combustion chamber or bowl 50 11, a stem portion 12, a bore 13 within said stem, a smoke duct 14 connecting the bottom of the bowl 11 with the bore 13, a cylindrical, downwardly-opening recess 15 beneath said bowl and separated therefrom and a 55 passage connecting said recess and the bore 13. A mouth-piece 16, of any suitable ma-

terial, is formed with a smoke duct 17 throughout its length and forms a continuation of the stem 12, being removably and replaceably secured thereto in any desired 60 manner such as a friction slip-joint (Figure 1) or by means of threaded engagement (Figure 2). The end of the smoke duct 17 adjacent the bore 13 is enlarged to form a cone or bell 18 opening into said bore. A 65 cup 19, preferably of metal or some other non-absorbing material, is formed to fit the recess 15 and is mounted therein with its opening downward and secured in some suitable manner to the body portion of the pipe. 70 The rim of the cup 19 is internally threaded to engage with threads on the edge of a closing plate 20, said plate being removable and replaceable to give access to the interior of the cup 19 at times and being provided 75 with a slotted boss 21, indented slot or other means adapted for engagement by the edge of a coin, knife blade or the like to facilitate rotation of said plate. A tube 22, preferably of non-absorbing material, extends 80 from an aperture in one side or corner of the cup 19 through the passage between the recess 15 and bore 13 and terminates in an enlarged end or bell 23 adjacent to and registering with the bell 18 of the mouth-piece 85 16, said bell 23 being adapted to entirely fill and close the open end of the bore 13. A tube 24, likewise of non-absorbing material and of less diameter than the tube 22, is adapted to register at one end with the 90 smoke duct 14 and thus provide a continuation of said duct, the other end of said tube intersecting the bell 23, extending within said bell and registering with the smoke duct 17 of the mouth-piece 16 and spaced 95 slightly from said mouth-piece. The tubes 22 and 24 may be formed integrally or may be welded, brazed, soldered or otherwise secured one to another in any manner to seal the joint between said tubes and the lesser 100 end of the tube 22 may be permanently sealed to the cup 19 or may fit snugly in an aperture formed for its reception in said cup. The space within the cup 19 is preferably 105 filled with absorptive material such as blotting paper, cotton or the like, to absorb and hold the liquids received in said cup and to prevent the return of said liquids through the tube 22 when the pipe is inverted or jarred. The absorptive material may conveniently be prepared in the form of a disc 110 to be readily inserted in said cup and may

be treated with chemicals or solutions to deodorize or neutralize the liquids absorbed thereby.

In the operation of my device, suction is applied to the end of the mouth-piece 16 in a common manner and smoke is drawn from the burning contents of the bowl 11 through the smoke duct 14 and tube 24 to the bell 23, thence through the smoke duct 17 to the mouth of the smoker. Any liquids or oils not in a gaseous state may be drawn with the smoke to the end of the tube 24 within the bell 23 where they are received by said bell and pass along the tube 22 to the cup 19 and are absorbed and held by the material within said cup. In like manner, any saliva which may be introduced into the smoke duct 17 of the mouth-piece is prevented from entering the tube 24 because of the spacing of said tube from said smoke duct, the saliva being diverted by the bell 18 into the bell 23 and thence through the tube 22 to the cup 19. Thus is provision made for collecting and confining the liquids and oils which tend to foul a smoking pipe, to the end that said pipe may be readily cleaned and may at all times be sweet and unfouled. No attempt is made to filter the smoke or to remove any of the products of combustion which are in a gaseous condition, it not being here advanced that such an attempt would be desirable.

It is easily apparent that my invention is adapted for use with varying types of pipes of practically any shape or material and that slight structural modifications may be made therein without departing from the principle of the invention, hence I do not wish to be limited to the specific constructions illustrated but only by the scope of the appended claims.

I claim as my invention—

1. A smoking pipe comprising a body portion having a stem, a bore in said stem, a bowl in said body portion, a downwardly-opening recess in said body portion beneath said bowl, spaced ducts connecting said bowl and said recess with said bore, a removable and replaceable moisture trap within said bore comprising intersecting tubes adapted to register with said ducts and a mouth-piece fixed to said stem and formed with the convergent end of a duct adapted to register with said trap. 45

2. A smoking pipe comprising a body portion having a stem, a bowl in said body portion communicating with a bore in said stem, a downwardly-opening recess in said body portion beneath said bowl, a receptacle within said recess, a removable and replaceable cover on said receptacle, a tube formed with a bell-shaped end within said bore and communicating with said receptacle, a second tube intersecting and projecting within the bell-shaped end of said first tube and communicating with said bowl and a mouth-piece engaging said stem and formed with a duct adapted to register with the bell-shaped end of said first tube. 55 60

3. In a device of the character described, 70 a body portion formed with a stem, a bowl and a downwardly-opening recess beneath said bowl, a receptacle within said recess, a moisture trap within said stem communicating with said bowl and receptacle, said trap 75 comprising intersecting tubes, one of said tubes projecting within the enlarged end of the other tube, together with a mouth-piece engaging said stem and formed with a duct adapted to register with said trap. 80

Signed at Florence, in the county of Fremont and State of Colorado this 12th day of March, 1926.

IVAN A. HARRISBERGER.
